CLAIM

The ornamental design for a combined flower vase and picture frame, substantially as shown.

DESCRIPTION

FIG. 1 is a perspective view of a combined flower vase and picture frame showing my new design;

FIG. 2 is a top plan view thereof;

FIG. 3 is a rear elevational view thereof;

FIG. 4 is a side elevational view taken from the right of FIG. 1, the side opposite being a mirror image thereof;

FIG. 5 is a bottom plan view thereof.
